JOSEPH BERNARD DRESEL, OF WEIRTON, WEST VIRGINIA, ASSIGNOR TO THE PHELPS CAN COMPANY, OF BALTIMORE, MARYLAND, A CORPORATION OF WEST VIRGINIA.

FEEDING MEANS FOR CAN-BODY BLANKS.

1,202,685.

Specification of Letters Patent. Patented Oct. 24, 1916.

Application filed July 5, 1916. Serial No. 107,864.

To all whom it may concern:

Be it known that I, JOSEPH B. DRESEL, a citizen of the United States, residing at Weirton, in the county of Hancock and State of West Virginia, have invented a new and useful Feeding Means for Can-Body Blanks, of which the following is a specification.

This invention has reference to feeding means for can-body blanks and its object is to avoid certain objectionable features of feeding means heretofore employed for the purpose.

Prior to the present invention the can-body blanks, which consist of flat sheets of tin of appropriate size, were fed from the bottom of a pile by means of a suction mechanism pulling the bottom sheet of the pile downwardly into the path of feeding fingers, which in turn carried the sheet thus separated from the pile to the portion of the machine in which they were subsequently treated. On being moved from the neighborhood of the pile each sheet traveled under spring devices, which latter because of the manner of separating the sheet from the pile were liable to become roughened by engagement with the edge portion of the removed sheet, and in time the removed sheet would catch on the spring devices, thus causing clogging of the machine and necessitating the removal of the impediments caused by the clogging of the sheets before the operation of the machine could be resumed.

Both in the feeding mechanism as previously constructed and as constructed in accordance with the present invention the bottom sheet is engaged and pulled downwardly away from a pile of superposed sheets by a suction device engaging the bottom sheet at about the middle with the ends still supported, so that the sheet in being pulled away from the pile of sheets becomes bowed. In the machine for the subsequent treatment of the sheets it was customary to employ spring holding means, in the form of spring fingers, at an intermediate point and at the end portions of the sheet with such sheet progressing in a direction transverse of its length under the spring fingers until resting upon a table with the fingers pressing flat upon the top of the sheet. Because of the bowed shape of the sheet as pulled away from the pile the spring fingers toward the ends of the sheet were engaged thereby

at a considerable distance above the level at which the middle portion of the sheet engaged the corresponding intermediate spring finger, and it was because of the high point of engagement of the end portions of the sheet with the end spring fingers and the angle of engagement due to the bowing of the sheet that the end fingers where engaged ultimately became roughened or worn, and finally the sheets were liable to catch on the spring fingers so that the sheets became distorted and the operation of the machine as a whole was interfered with to a corresponding extent.

In accordance with the present invention the spring fingers engaging the end portions of the sheet are supplemented by presser devices so arranged that the wear of the spring fingers heretofore occurring is obviated and the sheet reaches the subsequent portions of the machine in the ordinary flat condition, whereby liability of distortion of the sheet and the troubles ensuing therefrom are wholly obviated.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:—Figure 1 is a side elevation of the feeding end of a locking machine for can bodies with the invention applied. Fig. 2 is an end elevation of the structure of Fig. 1, distant parts of the locker device being omitted. Fig. 3 is a plan view of the structure of Figs. 1 and 2. Fig. 4 is a perspective view of presser feet embodying the present invention and adjacent parts of the locker modified to adapt them to the presser feet. Fig. 5 is a section on the line 5—5 of Fig. 3.

Referring to the drawings there is shown the feeding end of a can-body locker 1 of known construction to which the structure of the present invention is particularly adaptable. Such locker is provided with a reservoir 2 for a pile 3 of can-body blanks from the bottom of which, as will presently

appear, the blanks are removed one at a time. The locker is supplied with legs 4 and a table 5, upon which latter the can body blanks are delivered from the pile 3. At one end the locker has a cross piece 6 at the mid point of which there is bolted a bracket 7 supporting a guide 8 for a reciprocatory member 9 provided at the upper end with a suction head 10 and at the lower end with an eccentric strap or ring 11. The plunger or reciprocatory member 9 is hollow for a portion of its length with the hollow interior communicating with the head 10 and with a flexible pipe 12 in turn connected with a suitable suction apparatus, whereby air is continually exhausted through the head 10. The eccentric strap encircles an eccentric 13 mounted on a countershaft 14 having journal bearings 15 in a drop portion 16 of the bracket 7. The eccentric 13 is secured to one end of the shaft 14 while at the other end thereof there is secured a sprocket wheel 17 connected by a sprocket chain 18 to another sprocket wheel 19 on a shaft 20 having a journal bearing 21 on one of the legs 4 of the locker.

The mechanism so far described may be the same or substantially the same as is already in use upon installed can-body lockers, except as the mechanism is changed to accommodate the present invention.

The reservoir 2 comprises end members 22 which may be of channel construction. These end members are joined at the top 35 by a bar 23 located near the ends of the channel members 22 adjacent to the table 5 of the locker. The bar 23 carries a stop finger 24 depending therefrom in the path of the pile 3 of can body blanks, and this finger has an angle end 25 provided with an elongated slot 26 through which there extends a bolt 27 traversing the bar 23, so that the finger may be adjusted lengthwise of the locker to properly position piles of can body blanks of different widths.

To provide for can-body blanks of different lengths the end channels 22 have their upper flanges connected to the bar 23 by bolts 28 extending through slots 29 in the bar 23. The lower webs of the channels 22 are connected by bolts 29 to a leg 30 on each of two terminal castings 31 made fast at appropriate points to the top of the table 5 by bolts 32 extending through elongated slots 33 in the castings 31, thus permitting the adjustment of the channels 22 toward and from each other in a direction cross-wise of the table 5, whereby the reservoir 2 may be made to accommodate and center 35 can body blanks of different lengths, the stop finger 24 performing the same service with respect to can-body blanks of different widths. By this means piles 3 of can body blanks may be centered over the suction head 10 with sufficient accuracy.

Secured to the under side of each leg 30 by means of bolts 34 is a plate 35 having slots 36 therein for the passage of the bolts 34, whereby the plate 35 may be adjusted. One edge of each plate 35 is formed with an upturned flange 37 constituting a rest or support for the pile 3 of blanks. By this means the pile 3 is supported close to its ends and the lowermost blank may be readily engaged by the head 10 and drawn downwardly away from the bottom of the pile while the extreme edge portions of the withdrawn plate remain in engagement with the flanges 37 and support the blanks above it.

Movable along the bed 5 in suitable grooves 38 formed therein are slide bars 39 usually termed trigger bars because they are arranged with catches or triggers to progressively propel the can bodies from the reservoir or magazine 2 to the locking mechanism. As the structure of these trigger bars forms no part of the present invention it is not shown in the drawings. Each trigger bar 39 terminates at one end in a nose 40 into the path of which the bottom one of the can bodies of the pile is drawn by the suction head 10 when the latter is lowered after being attached to the can body blank. The trigger bars 39 are moved by proper mechanism, not shown, in a direction to propel the downdrawn blank onto the table 5, after which the trigger bars return to a position to engage the next blank in order when it is drawn down by the suction devices.

On the table 5 and in the path of the can body withdrawn from the reservoir or magazine thereof is a spring presser finger 41 with an upturned end 42, the presser finger being closely related to the top surface of the table 5 so as to hold can body blanks close to the table with elastic pressure. There are other spring fingers 43 with upturned ends 44 located on opposite sides of the finger 41 at such distance therefrom that the trigger bars 39 are between the finger 41 and respective fingers 43. The upturned end 42 of the finger 41 is close to the magazine of can body blanks, while the upturned ends 44 of the fingers 43 are more distant therefrom.

Extending across the table 5 above the surface of the latter and above the finger 41 is a rock shaft 45 mounted in journal bearings 46 at the sides of the table. This rock shaft extends at one end beyond the corresponding side of the table and there has fast to it an arm 47 extending radially from the shaft. To the outer extremity of the arm 47 there is attached one end of a spring 48, the other end of which is made fast to a stud on an upright 49 secured to one side of the table 5. The tendency of the spring 48 is to pull the arm 47 downwardly, thus imparting to the shaft 45 a tendency to rock in the direc-

tion of constraint of the arm 47. Secured to the shaft 45 are other arms 50 each carrying at the outer end a spring 51 and at an intermediate point a rod 52. The spring 51 is connected at one end to the arm 50 and at the other end to an upturned toe or extremity 53 of an elongated shoe 54, which latter at a mid point is connected to the corresponding end of the rod 52 by a pivot pin 55. The 10 tendency of the spring 51 is to maintain the shoe 54 tilted, so that its heel is against the upper surface of the table 5 in line with a respective one of the spring fingers 43, while the upturned toe 53 of the shoe 54 is elevated and also in the general line of the respective spring finger 43.

The arm 47 rests upon the upper ends of an upright rod 56 mounted to slide in bearings 57 fast to the upright 49. At the lower end 20 the rod 56 carries a roller 58 bearing upon a cam 59 secured to the shaft 20 so as to at all times engage with and support the cam 58 and with it the rod 57.

The shoe 54 with the arm 50 and spring 25 51 and also the rod 52 constitute a presser foot for can bodies moved under the shoe 54. There are two such presser feet one in advance of each spring finger 43 in the direction of travel of the can bodies.

30 While a can body blank is being moved from the magazine on to the table 5 the central depressed portion of the blank is at a level substantially the same as the top of the table and readily moves under the spring finger 41 without engaging the upturned end 42 thereof at a high point to be forced by the upturned end toward the table.

The parts are so timed in operation that as the can body blank is removed from the 40 magazine and as the extremities of the blank are moving off from the flanges 37 the front edge of the moving blank is brought into engagement with the shoes 54, which at this time are tilted so that the heel portions are 45 upon the table 5 and the front portions 53 are elevated.

About the time that the can-body blank reaches the shoes 54 the cam 59 has moved sufficiently so that its high point previously 50 under the roller 58 has moved away from such position when the spring 48 is permitted to act to lower the shoes 54 toward the table 5, the springs 51 serving as elastic means for eliminating rigidity of the parts. 55 The can-body blank moving upon the table 5 is therefore gradually and evenly pressed down to the table, but with elastic pressure and the angle of the shoes 54 forming part of the presser feet becomes progressively 60 more acute with relation to the line of travel of the blank, so that there is no liability of any wearing or cutting action of the shoes 54 which would tend to form ridges to catch successive blanks and thus cause them to 65 bend or buckle and thereby become distorted

and interfere with the working of the machine.

In order to guide the blanks after being initially lodged on the table 5 as removed from the magazine there are provided elongated guide bars 60 with slots 61 for fastening bolts 62 permitting adjustments of these bars corresponding to the adjustments of the castings 31.

As each can-body blank is moved away 75 from under the presser feet the latter are tilted, that is, the fronts 53 are raised by rocking with the shaft 45, while the heels of the shoes 54 rest lightly on top of the table so that the presser feet are in position to permit moving the next can body blank onto the table from the magazine without interference. Then the presser feet lower into engagement with the can body so placed and hold it with elastic pressure while the trigger bars return into position to engage the next blank in order and to engage the already placed can blank to move it out of the way and toward the locker mechanism as the next succeeding can body blank is delivered 90 on to the table to be acted on in the same manner by the presser feet as the first-named can body.

The arrangement permits the successive placing of the blanks on to the table without 95 wear upon the finger 41 or the presser feet, wherefore there is no liability of catching of the can-body blanks upon any portion of the machine whereby the can blanks would be bent or buckled and so distorted in a 100 manner resulting in the clogging of the machine and the necessity of clearing it before it can proceed, such clearing meaning a delay in the operation which is both vexatious and costly.

105 What is claimed is:—

1. A feeding means for can-body blanks, comprising a magazine for a pile of the blanks, means for moving the blanks one at a time from the magazine, and holding means for the blanks after removal from the magazine, comprising elastically yieldable presser feet and actuating devices therefor timed in operation to move the presser feet into and out of engagement with the delivered can-body blanks in alternation with the means for removing can-body blanks from the magazine.

110 2. A feeding means for can-body blanks, comprising a magazine for a pile of blanks, means for moving the blanks one at a time from the magazine, rockable elastic presser feet in the path of the can-body blanks as removed from the magazine, and means for rock the presser feet timed in operation to actuate the presser feet in alternation with the movement of the blanks from the magazine.

115 3. A feeding means for can-body blanks, comprising a magazine for a pile of blanks,

- means for moving one blank at a time from the magazine, and tilttable presser feet for the blanks each comprising a shoe with means for tilting the shoe and elastic means 5 providing a yieldable backing for the shoe.
1. A feeding means for can-body blanks, comprising a magazine for a pile of blanks, means for delivering the blanks one at a time from the bottom of the pile, a table onto 10 which the blanks are delivered, spring fingers for receiving and holding the blanks on the table at intermediate and end portions of the blanks with the spring finger for engaging the intermediate portion of the blank 15 closer to the magazine than the other fingers, presser feet located between the second-named finger and the magazine, and means for rocking the presser feet toward and from the table to engage and release the blanks 20 and to hold the blanks in conjunction with the spring fingers.
2. In a feeding means for can-body blanks having a magazine for the blanks and means for delivering the blanks one at a time from 25 the magazine, presser feet for engaging the delivered blanks, each presser foot comprising a shoe, and means for moving the shoe into and out of engagement with a delivered blank consisting of a rock-arm with a hinge 30 connection between an intermediate portion of the rock-arm and an intermediate portion of the shoe, and a spring connecting the outer portion of the rock-arm with the corresponding outer portion of the shoe.
3. 6. A feeding means for can-body blanks, comprising a magazine for a pile of blanks, means for delivering the blanks one at a time from the magazine, and presser feet and operating means therefor comprising a rock- 35 shaft, rock-arms on the rock-shaft with one 40 of the rock-arms having a spring connection to a fixed portion of the machine for constraining the rock-shaft toward a predetermined position, and shoes connected to the other rock-arms, said connections including 45 a hinge connection and a yieldable connection, whereby the shoes will be in angular relation to an advancing blank when first presented to the shoes, and will then press flat upon the shoes during further movement of 50 the blanks under the shoes.
4. A feeding means for can-body blanks, comprising a magazine for a pile of blanks, supports for the end portions of the pile of blanks, suction means for moving the lower- 55 most blank away from the pile, a table onto which the blanks are delivered, means for moving the blank drawn away from the bottom of the pile onto the table, spring fingers for engaging the blank when on the table, 60 presser feet between the magazine and certain of the spring fingers, said presser feet comprising shoes and rock-arms with hinge and otherwise rigid connections between the rock-arms and shoes at intermediate points 65 of both, and spring connections between the outer end portions of the rock-arms and shoes, a rock-shaft carrying the rock-arms, another rock-arm on the rock-shaft, a spring connected at one end to the free end of the 70 last-named rock-arm and at the other end to a fixed portion of the machine, a slidtable rod engaging the last-named rock-arm, and a can for engaging the rod to move it in the direction of its length. 75

In testimony that I claim the foregoing as my own, I have hereto affixed my signature.

JOSEPH BERNARD DRESEL
